Application April 24, 1935, Serial No. 18,051
In Germany May 3, 1934

21 Claims. (Cl. 253—69)

The present invention relates to steam and gas turbines and has particular relation to an improved construction for the last rings or rows of moving blades of such turbines.

It is well known that the performance of gas or steam turbines is largely determined by the characteristics of the last blade rows, especially by the peripheral velocity and fluid outlet area of the very last moving blade row. The U. S. patents to Ljungstrom, Nos. 1,897,172 and 1,942,608, disclose a method of constructing moving blade rows with greater peripheral velocities and outlet areas than were theretofore possible. This result is attained by making the moving blades of relatively thin sheet metal strips, formed along centrifugal catenary curves, and securing the ends thereof to axially separated annular blade carrier rings which, in turn, are interconnected through the medium of a framework. In this way, an appreciably lighter blade construction is obtained which makes it possible to operate at correspondingly higher peripheral velocities and with greater outlet areas. However, the peripheral velocity and size of these outlet areas are limited by the load or stress which the blade carrier rings can safely withstand as well as by the permissible load on the framework interconnecting the blade rings.

It is therefore one of the objects of the present invention to remove this limitation and to provide a moving blade row of novel construction wherein the loads or stresses set up due to centrifugal force may be safely taken up even though the size and peripheral velocity of the blades and their supporting structure are increased beyond present limits.

Another object is to provide a turbine rotor with new and structurally improved means for supporting and interconnecting the blade carrier rings.

A further object is to provide a novel supporting structure for the last row of moving blades of a steam or gas turbine which structure is lighter and stronger than those hitherto known and cooperates with the preceding portion or stage of the turbine in a novel manner for the supply of the motive fluid to said last row of blades.

Still another object is to provide novelly constructed means for securely attaching the ends of arched turbine blades to their carrier rings which means are both light in weight and sufficiently strong to anchor the blades ends against displacement under the relatively powerful centrifugal forces developed at high speeds of rotation.

The invention is characterized essentially by the fact that both blade carrier rings are supported by radially or substantially radially extending members, at least one of which assumes the form of an annular ring made up of struts, spokes or the like, between which the driving medium flows to the blades. The carrier ring supporting members are then connected together by a drum or ring, or by the turbine shaft itself, the diameter of this connecting element being materially smaller than that of the blade carrier rings. This form of construction makes it possible to take up appreciably greater centrifugal forces and permits the blade carrier rings as well as the blades themselves to be of greater diameter and consequently to attain greater peripheral speed, whereby at a given R. P. M. a correspondingly greater performance per turbine outlet may be obtained.

Further objects, features and advantages of the invention will become apparent upon consideration of the detailed description of the invention which follows. Although several different embodiments of the invention are described and illustrated in the accompanying drawings, it is to be expressly understood that these drawings are for purposes of illustration only and are not to be construed as defining the limits of the invention, reference being had to the appended claims for this purpose.

In the drawings, wherein like reference characters indicate like parts throughout the several views:

Fig. 14 is a side view of a portion of another construction according to the present invention for supporting a blade carrier ring.

Fig. 15 is a section taken substantially along line 15-15 of Fig. 14.

Fig. 16 is a cross section through a blade carrier ring and the end of the blade carried thereby showing the novel form of blade securing means provided by the present invention.

Referring now to the embodiment illustrated in Figs. 1, 2, and 3, the invention is there shown in its application to an axial turbine. The steam enters the turbine through inlet 8 and impacts against a speed rotor 9 and then a large number of axial stages 10. 11 are passageways for tapping steam for feed water preheating. Following the last axial moving blade row 12 a guide blade row 13 is provided. Insofar as the drawings relate to conventional turbine parts they should be understood without further description; the following description is therefore limited to the novel parts of the turbine constituting the present invention.

From guide blades 13 the steam flows, as indicated by arrows 14, through a ring of struts or spokes 15 in a substantially axial direction, and then radially through the last moving blade row consisting of arched or sheet metal blades 16. After leaving blades 16, the steam exhausts through the diffuser guide blade row 17 to the outlet 18. The arched blades 16 of this modification, the form of which is shown in Figs. 1 and 2, are preferably made of relatively thin sheet metal, as of stainless steel, and the ends thereof are suitably secured in a pair of blade carrier rings 19 and 20. Blade carrier ring 20 is supported by turbine disk 21 with which it is integral. Blade carrier ring 19, on the other hand, is supported by the struts or spokes 15 which, as shown in Fig. 3, form an annular ring 50 through which the steam flows to blades 16 constituting the last moving blade row of the turbine. Struts 15, in turn, are carried by a disk 22 which, like disk 21, is concentric with the turbine shaft. Blade carrier ring 19, struts 15 and disk 22 are 55 preferably integral with one another. Runner disks 21 and 22 are securely interconnected by means of a ring or drum 23, the diameter of which is, as shown, materially less than the diameter of carrier rings 19 and 20.

In the aforementioned prior constructions of arched blades, the latter are generally mounted on self-supporting blade carrier rings. The load or stress upon such self-supporting rotating rings, as is well known, increases proportionately with the square of the peripheral speed. It is there-

fore impossible to increase the size of these rings beyond a certain diameter without rendering them incapable of withstanding the stresses set up by centrifugal force during operation at normal turbine speeds, a condition which in turn limits the size and outlet area of the last moving blade row. This necessary maintenance of the diameter of the blade carrier ring within relatively narrow limits also makes it difficult to introduce the steam to the arched blade row, in which it flows radially, from the last moving blade row of an adjacent axial flow portion of the turbine. These defects are overcome, however, in the present invention by supporting the carrier rings of the arched blades by means of radially or substantially radially arranged members, the outer diameter of which is substantially equal to the outer diameter of the last moving blade row of the axial flow portion of the turbine—in the present specific instance blade carrier ring 20 is supported by a disk 21 and blade carrier ring 19 by a ring consisting of struts 15 and disk 22.

Since the centrifugal forces acting during rotation of the parts supporting the blade carrier rings cause the said parts to distend, the carrier rings will also be distended to a corresponding extent, whereby they are subjected to the same stresses as prevail in the radially extending supporting parts. In other words, the load created by centrifugal force is distributed and divided between the blade carrier rings and their radially extending supporting elements, the major portions thereof being absorbed by the latter elements. The stresses in the blade attachment rings can therefore be maintained lower than in self-supporting rings; by the same token, it is possible to provide blade carrier rings of appreciably greater diameter without setting up stresses greater than those that can be safely carried. Moreover, since the arched blades 16 are made of relatively thin sheet metal, i. e., they are very light in comparison with conventional turbine blades, the blade carrier rings may be made of a diameter as large as the outer diameter of the last moving blade row of normal high-performance axial turbines.

The light construction of an arched blade, radial flow wheel according to the present invention also makes it possible to add another low pressure rotor at the outlet side of the present-day conventional limit turbines of the axial type, said rotor operating at an appreciably higher peripheral speed and employing a greater outlet area than was heretofore possible with known outlet blade rows. As a result of the higher peripheral speed of the last blade row, a relatively greater heat drop may be produced therein, so that the next to the last rotor may operate at an appreciably higher pressure and with a correspondingly smaller volume of steam. By the addition of a blade row constructed in accordance with the present invention, it thus becomes possible to increase the maximum performance of a turbine at a given R. P. M. to from three to four-fold the value heretofore attainable. The magnitude of the heat drop in the last rotor presents the further advantage that the moisture in the steam does not attain a high value until expansion takes place in the last blade row, whereby danger of blade erosion is correspondingly minimized.

As shown in Fig. 1, supporting struts 15 and the outer part of disk 21 are inclined toward the radial direction, or are formed along a catenary curve in continuation of that of blades 16, so that

upon rotation there is no bending stress but only a tensile stress in these parts, notwithstanding the axial force exerted by the arched blades.

Struts 15 are also preferably tapered outwardly 5 (that is, in a radial direction) and of such cross section at right angles to their length as to offer a minimum of resistance to the flow of the steam or other driving medium as it passes from fixed 10 guide blades 13 to moving blades 16. Fig. 4 shows 15 a preferred embodiment of blades 12 of the last axial blade row, as well as of guide blades 13 and struts 15. As indicated by the velocity diagrams 20 of Fig. 4, the driving medium leaves the moving blades 12 at the relative outlet velocity w_2 . By a 25 composition of the relative outlet velocity w_2 with the peripheral velocity u of blades 12 there is obtained the absolute outlet velocity c_2 . This velocity is converted in the fixed guide blades 13, 30 preferably without expansion, into inlet velocity c_1 into the ring of struts 15 which also rotates at peripheral speed u . By a composition of the inlet velocity c_1 with the peripheral velocity u , there is obtained the relative inlet velocity w_1 . The guide 35 blades 13 are preferably constructed in such manner that the relative inlet velocity w_1 into the rotating strut ring 15 is axially directed. The guide 40 blades can be twisted in known manner so that the same inlet angle of the driving medium is produced along the entire length of the struts independently of the variable peripheral velocity of 45 the latter and of the variable radius thereof. Of course, if desired, struts 15 may be disposed at a certain angle relative to the axial direction also. However, for constructional reasons, the embodiment 50 of struts with an axially extending cross section as shown in Fig. 4 is to be preferred.

The driving medium leaving the arched blades 16 is passed between housing walls 24 and 25 (Fig. 1), which are formed as an annular diffuser. 40 Guide blades 17, which are suitably secured in housing walls 24 and 25, are preferably so formed that they also act as a diffuser for the outgoing driving medium. This results, upon decreasing speed, in a compression of the outgoing driving 45 medium, thus reducing the outlet loss. The guide blade ring 17 offers the further advantage that, when the turbine is idling, the driving medium surrounding blades 16 practically forms a ring of steam or gas which rotates with blades 16, where- 50 by turbulent currents within the exhaust casing are avoided and power consumption during idling is reduced to a minimum; also, this construction protects the blades 16 from the dangerous eddy currents which otherwise arise, particularly if the 55 vacuum is destroyed.

Outlet 18 of the turbine preferably assumes the form of a spiral casing 26, whereby current losses between the last rotor and the condenser are reduced to a minimum and whereby a diffuser action, and thus a consequent reduction in outlet 60 losses, may be obtained. Spiral casing 26 is preferably made of relatively thin sheet metal. In order that the casing may be rigid, however, the diffuser casing walls 24 and 25 which form the 65 outlet from blades 16 are connected together by means of a ring of streamlined struts 27. As shown in Fig. 2, struts 27 are preferably made in the form of an annular framework, whereby great 70 solidity as well as the requisite rigidity of the turbine casing is obtained. The direction of flow of the driving medium through the blades 16, the diffuser guide blades 17 and the spiral casing 18 is shown by arrow 28 in Fig. 3, arrow 79 indicating the direction of rotation of blades 16.

75 Another embodiment of the spiral casing is

shown in Fig. 6. In this instance, the turbine 29 is provided with two laterally arranged condensers 30 and 31, the spiral casing being correspondingly subdivided into two parts 32 and 33.

As shown by way of example in Fig. 5, the 5 blade row according to the present invention may also advantageously be used as the last rotor either for radial flow turbines or for combined radial and axial flow turbines. In the embodiment of Fig. 5, the driving medium first passes 10 through a radial turbine consisting of the moving 15 blade rows 34 and the guide blade rings 35, and then through two stages of an axial turbine consisting of guide blades 36 and moving blades 37. From the last row of moving blades 37 the driving 20 medium passes through a radial flow low pressure stage constructed in accordance with the present invention—that is, through guide blades 38, struts 39 and arched blades 40 into the outlet casing, the latter being not shown on the 25 drawing for the sake of clearness. In this embodiment, the turbine rotor is supported only at the right end as viewed in the drawings, i. e., floating y.

As another exemplary embodiment of the present 25 invention, Figs. 7 and 8 show the application thereof to a double axial flow low pressure turbine having a common outlet. In this case, the driving medium flows first in opposite directions through the two axial blade systems 41 and 30 42, the quantities thereof leaving said systems then combining and flowing through the arched 45 blades 43 into outlet casing 44. Arched blades 43 are suitably secured to rings 45 and 46. In contrast to the foregoing illustrative embodiments, in this case both blade carrier rings 45 and 46 are supported by struts 47 and 48 which, in turn, are secured to or formed integrally with disks 49 and 50. These disks are mounted on the 50 turbine shaft 51 together with the rotors of the 40 axial stages. The diffuser blades of this embodiment are subdivided by means of a separator ring 54 into two diffuser blade rows 52 and 53, the 55 blades of which are inclined slightly from ring 54 toward the turbine axis. This construction 55 offers the advantage, among others, that the water of condensation thrown from the outermost points of arched blades 43 does not strike the diffuser blades but instead is collected on the relatively thick ring 54. The fact that the diffuser 60 guide blades 52 and 53 are axially inclined tends to cause whatever condensate is deposited on these blades to run toward the ends thereof, thereby preventing it from dropping down onto the arched blades 43. As shown in Fig. 8, outlet 65 casing 44 in this modification does not assume the form of a spiral but it is symmetrical in form. Accordingly, the diffuser blades 52 and 53 are 70 preferably so formed that the driving medium leaves them in a radial direction.

Figs. 9, 10, and 11 show another modification of the invention, on an enlarged scale. In this embodiment, ring 55 which carries one end of each of the blades assumes the form of a polygon, the 75 number of sides of which corresponds to the number of arched blades. This construction makes it possible for the bases of the arched blades, as well as the blade attachment, to be rectilinear. Accordingly, each blade end is provided with an enlargement which may be inserted 80 into one of the straight dovetail-shaped grooves provided obliquely on the periphery of the carrier ring 55, as shown on an enlarged scale in Fig. 11a. As hereinbefore described, the carrier ring 55 is supported by struts 56 and disk 57. 85

Due to the large centrifugal forces which arise during rotation of the turbine rotor, the blades produce a bending stress in the blade carrier ring 55, whereby ring 55, which acts as a supporting beam, is bent between each pair of struts 56. In order to retain this bending force within allowable limits, it is necessary in certain cases to provide a large number of struts 56. In such cases, as shown in Fig. 10, it may be advantageous to provide struts 58 which are subdivided at the outer part thereof into two or more branches 59 and 60. Arrow 61 in Fig. 10 indicates the path of the driving medium relative to the rotating blade wheel.

In the exemplary embodiment shown in Figs. 12 and 13, the blade carrier ring 62 is circular and is provided with a circular dovetail-shaped blade groove 63. The blade bases are correspondingly arcuate in form and enlarged in cross section similarly to the showing of Fig. 11a. In this modification, drum 66 which interconnects supporting disks 64 and 65, is carried by a disk 67.

Figs. 14 and 15 show another modification wherein the arched blades 68 are again carried by a circular ring 69. In contrast to the foregoing construction, however, struts 70 which support carrier ring 69 are each made separate and are individually securable by separate connections to both ring 69 and disk 71. In the form shown, each end of each strut 70 is bifurcated or forked, the inside surfaces of each fork being grooved to form sawtooth-shaped threads corresponding to similar threads 72 formed on the inner surface of carrier ring 69 and on the outer edge of disk 71. In assembling a rotor of this construction, the forked ends of struts 70, which are spread apart sufficiently to allow passage over the threaded portions 72, are placed over said threads and are then brought into rigid clamping engagement therewith, as by a rolling operation. In most cases, however, it is advantageous, as shown in the previous modifications, to make the blade carrier ring, struts and disk integral, whereby greater strength and less weight result.

At high peripheral speeds, such as are employed with a turbine rotor constructed according to the present invention, powerful centrifugal forces are produced, notwithstanding the relatively light character of the arched blades, and it is therefore important that the attachment of the blades in the carrier rings be particularly secure and also that the attachment and the blade carrier ring be as light as possible.

Fig. 16 shows a construction which is particularly well suited for this purpose. The enlarged blade base 73 is provided with arcuate sawtooth-shaped threads or members 74 which fit corresponding recesses formed in the walls of the usual blade base receiving groove of the blade carrier ring 75, on the one hand, and in an arcuate filler member 76, on the other. Filler member 76 is also provided with sawtooth-shaped threads 77, whereby it is connected to the blade carrier ring 75. The blades are assembled with the carrier ring by first inserting a blade base 73 in the groove of the carrier ring in such position that its threads 74 engage the recesses formed in one side wall of the groove. Then a filler member 76, which may be of the same length as or shorter than the blade base, is inserted into an offset portion of the peripheral groove of the carrier ring 75 with its threads 77 engaging the recesses formed in the other side wall of the groove and is moved in the peripheral direction until it comes into interlocking toothed engagement with the threads

74 of the blade base. It will be noted that the combined width of filler member 76 and blade base 73 is greater than the width of the carrier ring groove at its narrowest point so as to effectively prevent the blade from being pulled out of the groove by centrifugal force. As shown in Fig. 12, an intermediate space 78 is provided between each two successive blades in order that the last blade may be inserted. This is accomplished by moving all the blades together as closely as possible until there is a sufficiently large intermediate space provided into which the filler member for the last blade may be inserted. Since the described blade attachment produces only relatively small bending stresses on the halves 15 of the blade carrier ring encompassing the blade base, the blade carrier ring may be made relatively thin and light, which is of great importance at its high peripheral speed.

It will be obvious that the present invention is not limited in its scope to the particular constructions described and illustrated, but is capable of a variety of mechanical embodiments. For example, it is obvious that, in the construction shown in Fig. 16, the plurality of threads and recesses formed on the blade base and filler member and in the walls of the carrier ring groove may be replaced by single shoulders and recesses, or equivalent means operating upon an interlocking or wedging principle. Various other changes, which will now become apparent to those skilled in the art, may be made in the form, details of construction and arrangement of the parts of the disclosed embodiments without departing from the spirit of the invention. Reference is therefore to be had to the appended claims for a definition of the limits of the invention.

What is claimed is:

1. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings at its outer periphery, at least one of said members having openings formed therein through which the turbine driving medium may be supplied to said blades.

2. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members lying in planes substantially perpendicular to the rotor shaft of the turbine and axially spaced by an amount substantially equal to the axial spacing of said carrier rings, each of said members including a disk concentric with and connected to the turbine shaft to the outer periphery of which is secured one of said blade carrier rings, at least one of said members having openings formed

- therein through which the turbine driving medium may be supplied to said blades.
3. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings, each of said members consisting of a central disk portion from the periphery of which radially extend a plurality of circumferentially spaced struts, the outer ends of said struts being secured to one of said carrier rings and the spaces between said struts serving as openings through which the turbine driving medium may be supplied to said blades.
4. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, at least one of said members consisting of a central disk portion from the periphery of which radially extend a plurality of circumferentially spaced struts, the outer ends of said struts being secured to one of said carrier rings and the spaces between said struts serving as openings through which the turbine driving medium may be supplied to said blades, said disk portion, struts and carrier ring being made in one piece so as to provide an integrally formed structure of increased strength.
5. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, one of said members consisting of a central disk portion from the periphery of which radially extend a plurality of circumferentially spaced struts, the outer ends of said struts being secured to one of said carrier rings and the spaces between said struts serving as openings through which the turbine driving medium may be supplied to said blades, the other member consisting of a solid disk.
6. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members lying in planes substantially perpendicular to the rotor shaft of the turbine and axially spaced by an amount substantially equal to the axial spacing of said carrier rings, each of said members consisting of a disk concentric with and connected to the turbine shaft and a plurality of circumferentially spaced struts extending radially from the periphery of said disk, the outer ends of the struts of each member being secured to one of said blade carrier rings and the spaces between said struts serving as openings through which the turbine driving medium may be supplied to said blades from the two axial flow portions of the turbine.
7. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings at its outer periphery, at least one of said members having openings formed therein through which the turbine driving medium may be supplied to said blades, the outer peripheral portion of each of said members adjacent the connection with its associated blade carrier ring being curved toward the other member along a substantially catenary curve similar to that of said blades.
8. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, at least one of said members consisting of a central disk portion from the periphery of which radially extend a plurality of circumferentially spaced struts, said struts being tapered in the direction of their extension from said disk portion and having secured to their outer ends one of said carrier rings, the spaces between said struts serving as openings through which the turbine driving medium may be supplied to said blades.
9. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members lying in planes substantially perpendicular to the rotor shaft of the turbine and axially spaced by an amount substantially equal to the axial spacing of said carrier rings, each of said members consisting of a disk concentric with and connected to the turbine shaft and a plurality of circumferentially spaced struts extending radially from the periphery of said disk, the outer ends of the struts of each member being secured to one of said blade carrier rings and the spaces between said struts serving as openings through which the turbine driving medium may be supplied to said blades from the two axial flow portions of the turbine.

cluding a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine; said members being axially spaced by an amount substantially equal to the axial spacing of said carrier rings and each being secured to one of said rings, at least one of said members consisting of a central disk portion from the periphery of which radially extend a plurality of circumferentially spaced struts, the outer ends of said struts being bifurcated and secured to one of said carrier rings, the spaces between said struts serving as openings through which the turbine driving medium may be supplied to said blades.

10. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, at least one of said members consisting of a central disk portion from the periphery of which radially extend a plurality of circumferentially spaced struts, the outer end of each of said struts being subdivided into at least two branches and the ends of said branches being secured to one of said carrier rings, the spaces between said struts serving as openings through which the turbine driving medium may be supplied to said blades.

11. A turbine blade supporting structure according to claim 3 wherein each of said struts is streamlined in the direction of flow of the turbine driving medium through the openings between said struts.

12. A turbine blade supporting structure according to claim 3 wherein each of said struts is provided with a cross section which is elongated in a direction parallel to the turbine shaft.

13. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, at least one of said members consisting of a central disk portion, a plurality of circumferentially spaced struts ex-

tending radially outward from the periphery of said disk portion, and means for securing the opposite ends of each of said struts to said disk portion and one of said carrier rings, respectively, the spaces between said struts serving as openings through which the turbine driving medium may be supplied to said blades.

14. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, at least one of said members consisting of a central disk portion, sawtooth-shaped threads formed on the peripheral surface of said disk portion, a plurality of circumferentially spaced struts extending radially outward from the periphery of said disk portion, one end of each of said struts being bifurcated and having threads formed in the inner surfaces of said bifurcated portion corresponding to and interlocking with the threads on said disk portion, and means for securing the other end of each of said struts to one of said carrier rings, the spaces between said struts serving as openings through which the turbine driving medium may be supplied to said blades.

15. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings at its outer periphery, at least one of said members having openings formed therein through which the turbine driving medium may be supplied to said blades, and means for interconnecting said members at points intermediate their peripheries and their centers.

16. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings at its outer periphery, at least one of said members having openings

formed therein through which the turbine driving medium may be supplied to said blades, and means for interconnecting said members comprising a cylindrical drum element coaxial with the turbine rotor shaft and having a diameter less than that of said blade carrier rings.

17. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings at its outer periphery, at least one of said members having openings formed therein through which the turbine driving medium may be supplied to said blades, a disk parallel to and intermediate said members coaxial with said turbine shaft, and a substantially cylindrical drum element secured to the periphery of said disk and connected at its ends to said members, the diameter of said disk and drum element being less than that of said blade carrier rings.

18. In a steam or gas turbine of the type including a radial flow stage comprising a pair of axially spaced rotatable blade carrier rings to which are secured the ends of a plurality of relatively thin sheet metal blades each of which is curved outwardly from the turbine rotor shaft in a centrifugal catenary curve, means for supporting said blade carrier rings and blades and for absorbing the stresses set up therein by centrifugal force comprising a pair of members concentric with and connected to but lying in planes substantially perpendicular to the rotor shaft of the turbine, said members being axially spaced by an amount substantially equal to the axial spacing of said carrier rings and each being secured to one of said rings, at least one of said members consisting of a central disk portion from the periphery of which radially extend a plurality of circumferentially spaced struts, the

outer ends of said struts being secured to one of said carrier rings and the spaces between said struts serving as openings through which the turbine driving medium may be supplied to said blades, and a plurality of stationary guide blades arranged adjacent the path of rotation of said struts for directing said driving medium toward said openings.

19. In a rotor for a steam or gas turbine, a central disk, a plurality of circumferentially spaced struts extending radially from the periphery of said disk, and a blade carrier ring secured to the outer ends of said struts, said blade carrier ring including means for receiving and holding the ends of a plurality of turbine blades and the spaces between said struts serving as openings through which the turbine driving medium may be supplied to said blades.

20. A rotor for a steam or gas turbine comprising a pair of axially spaced rotatable disks, a plurality of circumferentially spaced struts extending radially from the periphery of one of said disks, a blade carrier ring secured to the outer ends of said struts, a second blade carrier ring secured to the periphery of the other disk, and a plurality of relatively thin, arched sheet metal blades extending between said carrier rings and having their ends secured thereto, the spaces between said struts serving as openings through which the turbine driving medium may be supplied to said blades.

21. A rotor for a steam or gas turbine comprising a pair of axially spaced rotatable disks, a plurality of circumferentially spaced struts extending radially from the periphery of one of said disks, a blade carrier ring secured to the outer ends of said struts, a second blade carrier ring secured to the periphery of the other disk, a plurality of relatively thin, arched sheet metal blades extending between said carrier rings and having their ends secured thereto, the spaces between said struts serving as openings through which the turbine driving medium may be supplied to said blades, and means for interconnecting said disks comprising a drum-like member substantially coaxial with and having its ends secured to said disks, the diameter of said member being substantially equal to the diameter of said strut supporting disk.
